UNITED STATES PATENT OFFICE.

MARTIN JOHNSEN AND FREDERICK C. HOLLING, OF ANTIOCH, CALIFORNIA.

DOOR-OPERATING MECHANISM.

Application filed October 19, 1925. Serial No. 63,283.

This invention relates to improvements in door operating mechanisms and particularly to a device for controlling the opening and closing of double garage doors of 5 the usual swing type.

The principal object of our invention is to provide a mechanism for the purpose so constructed and arranged that as an automobile approaches the garage it will automatically cause the doors to open, and when the car moves into the garage it will cause the doors to automatically close. Then when the doors have been again caused to open by a simple manual operation on the part 10 of the driver of the car from his seat, the car on backing out from the garage to a point clear of the same will again automatically cause the doors to be closed, ready for the next opening movement upon the return of the car to the garage.

It will therefore be unnecessary for the driver to leave the car to either open or close the doors from the outside so that he may remain under cover at all times—a feature of considerable benefit and merit, especially in inclement weather.

These objects we accomplish by means of such structure and relative arrangement of parts as will fully appear by a perusal of 30 the following specification and claims.

In the drawings similar characters of reference indicate corresponding parts in the several views:

Fig. 1 is a top plan view foreshortened 35 and of a somewhat diagrammatic nature, of the entire operating mechanism.

Fig. 2 is a sectional elevation of similar character showing the position of the parts after the doors have been closed by a car 40 leaving the garage.

Fig. 3 is a similar view showing the doors as opened after the passage of a front wheel of the car over the control mechanism, while moving toward the garage.

Fig. 4 is a similar view showing the position of the control mechanism as moved by 45 the passage of the rear wheel of the car while moving toward the garage.

Fig. 5 is a fragmentary sectional elevation 50 of the garage only, showing the interior door closing mechanism as operated by the car arriving inside the garage.

Fig. 6 is a sectional elevation of the complete structure, showing the exterior 55 control mechanism as being actuated by the front wheel of the car, to close the doors

after the car has moved out of the garage.

Figs. 7 and 8 are fragmentary views of the exterior door opening control member in neutral and operative positions corresponding to the position of the parts in Figs. 2 and 3.

Fig. 9 is a top plan view of the exterior control structure with the top plates removed.

Referring now more particularly to the characters of reference on the drawings, the numeral 1 denotes a casing of suitable dimensions sunk in the runway 2 leading to the garage 3 a certain distance from the latter. The casing is disposed in the path of the wheels on one side or other of the car moving to or from the garage.

The top of the casing which is flush with the runway includes two longitudinally spaced and vertically movable plates 4 and 5 with a fixed plate 6 therebetween of a length such that any wheel cannot rest on both plates 4 and 5 simultaneously.

The rear plate 4 is farthest from the garage and is pivoted at one end transversely in the casing, the other end being free to be depressed. The forward plate 5 is nearest the garage and is similarly mounted in the casing.

Turnably mounted in the casing under the plate 5 is a shaft 7 on which is fixed a pair of transversely spaced members 8 which are of circular form concentric with the shaft except for a flat face A. The shaft is so disposed relative to the plate 5 that when the circular portion of the members 8 is uppermost the plate 5 rests thereon and is then horizontal and flush with the runway. When the faces A are uppermost 90 the plate may be depressed a certain distance.

One of the members 8 has four evenly spaced pins 9 projecting from one side thereof concentric with the shaft. These pins are arranged in the path of a horizontal catch 10 mounted in common with a rod 11 which projects rearwardly from said member 8 under the plate 4 and below the plane of the shaft 7. A compression spring 12 associated with the rod 11 tends to move said rod and catch forwardly. A flexible element 13 is attached to the rod ahead of the spring and extends thence rearwardly to and around a sheave 14 to a connection with the free end of the plate 4. A compression spring 15 of considerably greater strength 105

than the spring 12 is applied to said plate, and normally holds the latter in a horizontal position and the catch 10 in its innermost position.

5 It will therefore be seen that when the plate 4 is depressed by a wheel of a car, the spring 15 will be compressed, slackening the element 13, and allowing the rod 11 and catch 10 to move to a forward position. In 10 such position the catch engages one of the pins 9. When the weight is removed from the plate, the spring 15 acts to restore said plate to its normal position and pulls the rod rearwardly at the same time. This 15 causes the member 8 to be rotated and the extent of movement of the member 11 thus had is designed so as to be sufficient to just rotate said members 8 exactly one quarter turn. This is very important as will be 20 hereinafter seen.

The spring 15 is of such strength as to resist being compressed, and consequently the plate depressed, by any ordinary weight such as that of a person. The members 8 25 are also so positioned that when the car moves outwardly of the garage past the casing, after having caused the closing of the doors as hereinafter seen, the flat faces of said members 8 will then be in a vertical position ahead of the shaft 7, as shown in 30 Fig. 2. This is also important.

When a front wheel F of a car moving toward the garage depresses and then moves beyond the plate 4 as shown in Fig. 3, the members 8 will be rotated one quarter turn from the position shown in Fig. 2 to that shown in Fig. 3. This movement effects the opening of the doors 16 of the garage in the following manner:

40 Projecting inwardly from one of the doors toward the adjacent side of the garage when said doors are closed is a rigid arm 17 having a horizontal hook 18 on its inner end. A rigid link or connecting rod 19 is pivoted onto the other door and onto the arm 17 in such a manner that the opening and closing of both doors will take place simultaneously. The arm and rod are of course adjacent the top of the doors so as 45 not to interfere with the passage of the car thereunder.

50 Mounted in the garage in horizontal alignment with the hook 18 and disposed in a plane lengthwise of the garage is a rod 20 having a catch 21 on one end normally engaging the hook 18. (See Fig. 1.) A compression spring 22 on said rod normally holds the catch and hook in engagement.

60 A compression spring 23 is applied to the arm 17 and tends to cause the doors to open, but said spring cannot function as long as the catch 21 is engaged with the hook 18. A flexible element 24 is connected to the rod 20 and extends thence downwardly and around suitable direction changing sheaves

25 to a point below the level of the top of the casing 1. Said element then extends horizontally toward the casing and is connected to the upper and substantially vertical arm of a bellerank 26 mounted in the casing ahead of the members 8. The other and substantially horizontal arm of the bell-crank extends alongside one of said members 8 in the path of a single pin 27 projecting therefrom (see Figs. 7 and 8). This pin is so positioned on the member 8 as to be above and immediately adjacent the horizontal arm of the bellerank 26 when the member 8 is in the first position, as shown in Fig. 2. Thus when the member 8 is rotated a quarter turn as previously described, the pin depresses the member 26, causing the element 24 to be pulled. This in turn pulls the catch rod 20 rearwardly and moves the catch 21 clear of the hook 18. This enables 55 the spring 23 to function and the doors 16 are consequently forced open.

When the member 8 has thus made a quarter turn, the pin 27 becomes disengaged from the member 26, allowing the latter and 60 of course the rod 20 as well to return to their normal positions. The pin will not therefore again engage the arm 26 until the member 8 has made a full revolution.

This door opening is effected by the passage of the front wheel of an incoming car over the plate 4. Said wheel moving over the plate 5 will not cause the depression of the same, since the circular portion of the members 8 then bear against the under face 100 of said plate.

When the rear wheel R of the incoming car passes over the plate 4, it effects another one quarter rotation of the members 8, to the position shown in Fig. 4, but does not 105 cause the member 26 to be actuated, since the pin 27 has already passed beyond the same, as above stated.

Neither will said rear wheel cause a depression of the plate 5, since the circular portion of the members 8 are still engaged with the plate 5.

When the car has entered the garage and has arrived at its innermost position, the doors will be closed in the following manner:

Mounted in the floor of the garage at the inner end thereof in the path of one of the front wheels of the car are plates 28 and 29 hinged together. The forward plate 28 is pivoted at its forward end onto the floor, while the rear end of the rear plate 29 is free and rests on the floor. Said rear plate is connected to a horizontal flexible element 30 wound about a small drum 31 which is 120 mounted under the plate 29 below the floor. A spring 32 between the floor and the plates tends to maintain the same in a triangular position with their hinged edges uppermost, as shown for instance in Fig. 2. 125

A relatively large drum 33 is mounted in connection with the drum 31 and has a flexible element 34 wound thereon. This element extends from the drum over suitably disposed direction changing sheaves 35 to a connection with the upper end of one of the doors near the hinge thereof. This door is preferably that one to which the arm 17 is connected. The elements 30 and 34 are so wound on the respective drums that when the plates 28 and 29 are flattened out by the weight of a wheel thereon as shown in Fig. 5 the element 30 will be unwound from its drum 31, causing the rotation of the latter, while the element 34 will be wound onto its drum 33.

The drums are so proportioned in size relative to each other that a comparatively slight rearward movement of the rear plate 29 and element 30 will cause a circumferential movement of the drum 33 and will cause the doors to be pulled to a fully closed position against the pressure of the spring 23. When the doors are thus closed the hook 18 will automatically engage the catch 21, thus holding the doors closed.

To then open the doors by hand to enable the car to be backed from the garage, I provide a handle 36 preferably hanging where it can be grasped by the driver of the car from his seat. A flexible element 37 connected to said handle extends thence over suitable direction changing sheaves 38 to a connection with the rod 20, and is so arranged that a pull on said handle causes the catch 21 to be disengaged from the hook 18.

Before thus pulling the latch rod 20, the car must be backed toward the doors a sufficient distance to clear the front wheel from the plates 28 and 29, in order to slack up on the member 34 which if not released would hold the doors closed even though the catch 21 was disengaged from the hook 18. Upon this movement of the car being effected the doors will then move to their open positions.

The car may then back out of the garage. The rear wheel first passes over the plate 5, the members 8 under said plate being then in the same position as when said rear wheel passed over the plate when entering the garage, or as shown in Fig. 4. In other words the plate 5 will not be depressed.

When the rear wheel reaches and depresses the plate 4, the members 8 will be rotated another quarter turn, or so that the flat faces A are uppermost, as shown in Fig. 6. Therefore when the front wheel reaches the plate 5, the latter will be depressed, since the support previously provided by the members 8 is removed. When the front wheel passes over and depresses the plate 4, the members 8 are again moved through a quarter turn, raising the plate 5 to its normal level position and assuming their original position as shown in Fig. 2, ready for another door

opening movement upon the return of the car toward the garage.

The depression of the plate 5 causes the doors to be closed by means of the following structure.

Mounted in the casing under the plate 5 are toggle joint arms 39 and 40 pivoted together. The forward end of the arm 30 is turnably pivoted on the shaft 7, while the rear end of the other arm 40 rests on and is movable along the bottom of the casing. A drum 41 is turnably mounted on the shaft 7, about which drum is wound a flexible element 42 which extends to the free end of the arm 40.

Another lever drum 43 is mounted in fixed connection with the drum 41 and has wound thereon a flexible element 44 which extends from the casing toward the garage and passes over suitable direction changing sheaves 45 to a connection with one of the doors 16. This connection is preferably made at about the same point on the door as the connection of the element 34 therewith.

The elements 42 and 44 are so wound on their respective drums that when the element 42 is unwound from its drum, the element 44 is wound on its drum, and vice versa. The toggle arm structure is so disposed that when the doors are opened and the element 44 is pulled and unwound from the drum 43, causing the rotation of both drums, the toggle arms will be raised so that their connected ends bear against the under side of the plate 5. Then when the plate 5 is depressed by the front wheel F, the toggle arms are depressed and flattened out, causing the rear end of the arm 40 to move rearwardly. This unwinds the element 42 from its drum 41 and causes the element 44 to wind onto its drum 43. This of course pulls on the element 44 causing the doors to be pulled to a closed position.

The arms 39 and 40 then remain in their lowered position until the doors are again opened, which opening movement imparts a reversal of movement to the element 34, drums 41 and 43, and element 42; causing the arms 39 and 40 to be again raised to their neutral position.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described our invention what we claim as new and useful and desire to secure by Letters Patent is:

1. A door operating mechanism for garage doors including with a normally closed

door, a structure adapted to be actuated by the weight on a wheel of a vehicle approaching the garage for causing said door to automatically open, said structure including a 5 depressible element disposed in the path of a wheel ahead of the garage, means incorporated with said structure whereby such door opening actuation will only take place with every fourth passage of a wheel there- 10 over, a structure in the garage and actuated by an innermost wheel of the vehicle for then closing the door, hand means for then enabling the door to be opened without affecting the depressible element, and further 15 means actuated by a wheel of the vehicle after leaving the garage for again closing the door.

2. A door operating mechanism for garage doors including with a normally closed 20 door, a structure adapted to be actuated by the weight on a wheel of a vehicle approaching the garage for causing said door to automatically open, means for closing the door after the vehicle has entered the garage, 25 means for again causing the door to open, to enable the vehicle to leave the garage, means actuated by a wheel of the vehicle after leaving the garage for again closing the door, said last named means including a de- 30 pressible element mounted outside the garage in the path of movement of such wheel, and means incorporated with said structure whereby said element can only be depressed with every fourth passage of a wheel there- 35 over.

3. A door operating mechanism for garage doors including with a normally closed door, a structure adapted to be actuated by the weight on a wheel of a vehicle approach- 40 ing the garage for causing said door to automatically open, said structure including a depressible element disposed in the path of a wheel ahead of the garage, means incorpo- 45 rated with said structure whereby such door opening actuation will only take place with every fourth passage of a wheel thereover, a structure in the garage and actuated by an innermost wheel of the vehicle for then clos- 50 ing the door, hand means for then enabling the door to be opened without affecting the depressible element, further means actuated by a wheel of the vehicle after leaving the 55 garage for again closing the door, said last named means including a further depressible element mounted outside the garage in the path of movement of a wheel of the vehicle, and means likewise incorporated with said structure and controlled by the recurring de- 60 pression of the first named element for enabling said last named element to be depressed only with every fourth passage of a wheel thereover.

4. A door opening mechanism for garage doors including with a door, releasable 65 means normally holding the door closed,

means tending to cause the door to open, a depressible element mounted in the path of movement of a wheel approaching the garage and arranged to be depressed by such wheel, and a mechanism between the element 70 and the door holding means for causing the latter to be released upon the depression of said element; said mechanism including a rotatable member, a pin projecting laterally therefrom, a releasing arm for the door holding means projecting into the path of move- 75 ment of the pin, and means between the depressible element and said member for rotating the latter only through a quarter turn with each depression of the element, where- 80 by the arm will be actuated only once with every fourth depression of the element.

5. A door opening mechanism for garage doors including with a door, releasable 85 means normally holding the door closed, means tending to cause the door to open, a depressible element mounted in the path of movement of a wheel approaching the garage and arranged to be depressed by such wheel, means for releasing the holding 90 means, mechanism including a movable member moved by the depression of the element for actuating the releasing means, and means incorporated with said mechanism for causing such releasing means actuation to take 95 place only with every fourth depression of said element.

6. A door operating mechanism for garage doors including with a normally closed door, a depressible element in the path of a wheel ahead of the door, a second depressible element also in the path of a wheel and located between the first named element and the door, control means actuated by the de- 100 pression of the first element by a wheel of a vehicle approaching the garage for enabling the door to open, means controlled by the depression of the second element by a wheel of the vehicle leaving the garage to cause the door to close, and means associated 105 with the first named control means and ini- 110 tially actuated by the depression of the first element for preventing the second element from being depressed by a wheel of the vehicle approaching the garage after the first element has been actuated to enable the door to open.

7. A door operating mechanism including, with a normally closed door, a structure adapted to be actuated by the weight on a 120 wheel of a vehicle approaching the garage for causing said door to automatically open, said structure including a depressible element disposed in the path of a wheel ahead of the garage, means incorporated with said 125 structure whereby such door opening actuation will only take place with every fourth depression of the element, further means actuated by a wheel of the vehicle upon leaving the garage for again closing the door; 130

said further means including a depressible element disposed in the path of the wheels outside the garage, and mechanism associated with said structure and further means for preventing depression of the second element except after every fourth depression of the first element.

8. A door operating mechanism including, with a normally closed door, a structure adapted to be actuated by the weight on a wheel of a vehicle approaching the garage for causing said door to automatically open, said structure including a depressible element disposed in the path of a wheel ahead of the garage, means incorporated with said structure whereby such door opening actua-

tion will only take place with every fourth depression of the element, further means actuated by a wheel of the vehicle upon leaving the garage for again closing the door; 20 said further means including a depressible element disposed in the path of the wheels outside the garage, and means controlled by successive depressions of the first element for preventing depression of the second element except after every fourth depression of the first element. 25

In testimony whereof we affix our signatures.

MARTIN JOHNSEN.
FREDERICK C. HOLLING.
